UNITED STATES PATENT OFFICE.

ALFRED H. HUMPHREY, OF NEW YORK, N. Y.

GAS-STOVE.

1,311,895.

Specification of Letters Patent.

Patented Aug. 5, 1919.

Application filed October 16, 1917. Serial No. 196,862.

To all whom it may concern:

Be it known that I, ALFRED H. HUMPHREY, a citizen of the United States, residing at New York, New York, have invented certain new and useful Improvements in Gas-Stoves, of which the following is a specification.

This invention relates to improvements in gas stoves.

10 The main objects of this invention are:

First, to provide an improved gas stove which is highly efficient in the matter of heat radiation.

Second, to provide an improved gas stove 15 which may be made mainly of sheet metal and at the same time one which has a substantial and attractive appearance.

Third, to provide an improved gas stove 20 which is comparatively simple and economical in structure and at the same time strong and durable.

Further objects and objects relating to details and economies of construction and operation will definitely appear from the detailed description to follow.

I accomplish the objects of my invention by the devices and means described in the following specification. The invention is clearly defined and pointed out in the 30 claims.

A structure constituting a preferred embodiment of my invention is illustrated in the accompanying drawing forming a part of this specification, in which:

35 Figure I is a front elevation of a structure embodying the features of my invention.

Fig. II is a vertical central transverse section on a line corresponding to line 2—2 of 40 Fig. I.

Fig. III is a vertical transverse section on a line corresponding to line 3—3 of Fig. I.

Fig. IV is a detail horizontal section on a line corresponding to line 4—4 of Fig. I.

45 Fig. V is a detail vertical section on a line corresponding to the broken line 5—5 of Figs. II and III, showing details of the arrangement of the burner.

Fig. VI is a detail view partially in vertical section on a line corresponding to line 6—6 of Figs. II, III and IV, showing structural details.

50 Fig. VII is a detail vertical transverse section on a line corresponding to line 7—7 of Fig. I.

Fig. VIII is a detail horizontal section on

a line corresponding to line 8—8 of Figs. II and III, showing the arrangement of the rear legs.

Fig. IX is a detail horizontal section on a line 60 corresponding to line 9—9 of Figs. I, II and III, showing details of the front and hearth plate and corner uprights.

Fig. X is a perspective view of the main body parts prior to the assembling of the 65 other parts therewith.

Fig. XI is a plan view of the sheet metal blank from which the side and end walls are formed, the angles of the walls being indicated by dotted lines.

In the drawing similar reference characters refer to similar parts throughout the several views, and the sectional views are taken looking in the direction of the little arrows at the ends of the section lines. 75

Referring to the drawing, in the structure illustrated, I provide a body member comprising a back wall 1 and side walls 2 formed integrally of sheet metal. The blank for this body member is shown in Fig. 80 XI. The angles or bending lines are indicated by dotted lines.

The side walls 2 are provided with parallel portions 3 adjacent the back and forwardly diverging portions 4 terminating in 85 the outturned rolls or beads of considerable diameter constituting uprights 5. The side walls are connected by the front plate 6 having rolls or beads 7 at its upper and lower edges, the front plate being disposed between the side walls at the rear of the uprights 5 and secured thereto by bolts 8 disposed longitudinally through the beads and through the side walls and provided with nuts 9 clamping the side walls against the 95 ends of the front plate.

The upper edges of the side walls are inclined forwardly. The top plate 10, in the structure illustrated, is also formed of sheet metal and is conformed to suitable outline. 100 This top plate overhangs the rear wall and portions of the side walls.

Blocks 11 are secured in the corners of the body member and provided with upwardly projecting bolts 12 disposed through 105 openings in the top to receive the nuts 13 which are preferably ornamental. Arms 14 are conformed to the upper edges of the side walls and project forwardly from the top over the upper ends of the uprights 5. 110 These arms are secured to the top by the bolts 15 and to the side walls by bolts 16,

the arms having lugs 17 through which the bolts 16 are disposed. The front ends of the arms are secured to the uprights by the bolts 18 disposed longitudinally through the corner uprights. These corner uprights are provided with top and bottom caps 19. Legs 20 conformed to harmonize with the uprights are disposed on the bottoms thereof and secured by the bolts 18,—see Fig. VI.

10. The rear legs 21 are preferably sheet metal stampings angled in cross section to fit the corners of the body member and riveted thereto.

Within the body I mount a supporting plate 22 which is preferably a casting and has a depending flange 23 at its front edge and a series of burner openings 24. The plate has a seat 25 for the fireback 26. The radiants 27 are mounted in front of the fire back over the burner openings. A burner comprising a plurality of burner tubes 28 has tips 29 alined with the burner openings 24. The burners are mounted on the depending flange by means of the screws 30.

25. The supporting plate has an upwardly projecting flange 31 which retains the bottoms of the radiants, their upper ends being retained by the bail-shaped rod 32 pivoted on the side walls so that it may be swung to and from engaging position, it being capable of being swung down in front of the upper ends of the radiants, as shown in Fig. I, or upwardly to permit their ready removal, as desired.

The fire back has flanges 33 at its ends which project forwardly to protect the end walls 4.

30. The gas manifold 34 of the burner is secured to projecting ears 35 on the outer burner tubes, as shown in Fig. V. The manifold has a plurality of nozzles 36 spaced from but in alinement with the lower open ends of the burner tubes so that gas 35 is directed to the tubes. The gas supply pipe 37 is arranged through the rear wall and connected to the manifold.

A valve 38 controls the supply pipe, the valve having a stem 39 projecting forwardly 50 below the front plate 6 and centrally thereof, as shown in Fig. I.

55. A hearth plate 40 is secured at its rear edge to the supporting plate flange 23 to rest upon the front plate and is provided with a downwardly and rearwardly turned flange 41 which engages under the upper bead of the front plate.

I preferably provide a finishing and reflecting plate 42 disposed across the angle 60 formed by the supporting plate flange and the hearth plate, its upper edge being secured to the supporting plate and its lower edge resting on the hearth plate, as shown in Fig. II. This plate 42 has a flange 43 at its upper edge which fits into the rabbet

44 on the supporting plate securing a good finish at this point. The plate 42 is preferably of polished metal so that it provides a heat reflecting surface as well as constituting a finishing member. The upper end 70 of the fire back is held by a retaining member 45 which fits over the upper end of the fireback and has an arm 46 with a slot 47 therein secured to the rear wall 1 by means of the bolt 48. This means of attachment 75 provides means for adjusting the retaining member to the fireback. The rear wall preferably has a collar 49 thereon to which a ventilating pipe may be attached.

With the parts thus arranged they may 80 be economically produced and assembled. While many of the parts are of sheet metal the completed structure is strong and durable and attractive in appearance.

My improved gas stove is efficient in the 85 matter of heat radiation and quite economical in fuel consumption.

I have illustrated and described my improvements in one form in which I have embodied the same for the market. I have 90 not attempted to illustrate or describe various modifications in structural details which I contemplate as I believe the disclosure made will enable those skilled in the art to embody my improvements as may 95 be desired.

Having thus described my invention, what I claim as new and desire to secure by Letters Patent is:

1. In a gas stove, the combination of sheet 100 metal back and side walls, the side walls having rolls constituting uprights at their front ends, a sheet metal front plate having beads at its top and bottom edges and secured to said side walls by bolts disposed 105 longitudinally through said beads, a sheet metal top overhanging the rear wall and portions of the end walls, arms extending forwardly from said top above the upper edges of said end walls and secured thereto, 110 top attaching bolts secured at the rear corners of the body member projecting through said top, front legs disposed below said uprights, bolts disposed longitudinally through said uprights and engaging said top arms 115 and front legs, rear legs disposed at the rear corners of the body member, a supporting plate having burner openings therein and a depending flange at its front edge mounted within said walls, a sheet metal hearth plate 120 having a downwardly and rearwardly turned flange at its front edge resting on said front plate with its flange engaging below the top bead thereof, the rear edge of said hearth plate being secured to said 125 supporting plate flange, and a burner mounted on said supporting plate and provided with burner tips disposed in alinement with said burner openings.

2. In a gas stove, the combination of sheet 130

metal back and side walls, the side walls having rolls constituting uprights at their front ends, a sheet metal front plate having beads at its top and bottom edges and secured to said side walls by bolts disposed longitudinally through said beads, a sheet metal top overhanging the rear wall and portions of the end walls, arms extending forwardly from said top above the upper edges of said end walls and secured thereto, bolts disposed longitudinally through said uprights and engaging said top arms, a supporting plate having burner openings therein and a depending flange at its front edge mounted within said walls, a sheet metal hearth plate having a downwardly and rearwardly turned flange at its front edge resting on said front plate with its flange engaging below the top bead thereof, the rear edge of said hearth plate being secured to said supporting plate flange, and a burner mounted on said supporting plate and provided with burner tips disposed in alinement with said burner openings.

3. In a gas stove, the combination of sheet metal back and side walls, the side walls having rolls constituting uprights at their front ends, a sheet metal front plate having beads at its top and bottom edges and secured to said side walls by bolts disposed longitudinally through said beads, a sheet metal top overhanging the rear wall and portions of the end walls, arms extending forwardly from said top above the upper edges of said end walls and secured thereto, top attaching bolts secured at the rear corners of the body member and projecting through said top, front legs disposed below said uprights, bolts disposed longitudinally through said uprights and engaging said top arms and front legs, rear legs disposed at the rear corners of the body member, a supporting plate having burner openings therein and a depending flange at its front edge mounted within said walls, a sheet metal hearth plate having a downwardly and rearwardly turned flange at its front edge resting on said front plate with its flange engaging below the top bead thereof, the rear edge of said hearth plate being secured to said supporting plate flange, a sheet metal plate disposed with its upper edge against said supporting plate and its lower edge on said hearth plate, and a burner mounted on said supporting plate and provided with burner tips disposed in alinement with said burner openings.

4. In a gas stove, the combination of sheet metal back and side walls, the side walls having rolls constituting uprights at their front ends, a sheet metal front plate having beads at its top and bottom edges and secured to said side walls by bolts disposed longitudinally through said beads, a sheet metal top overhanging the rear wall and

portions of the end walls, arms extending forwardly from said top above the upper edges of said end walls and secured thereto, bolts disposed longitudinally through said uprights and engaging said top arms, a supporting plate having burner openings therein and a depending flange at its front edge mounted within said walls, a sheet metal hearth plate having a downwardly and rearwardly turned flange at its front edge resting on said front plate with its flange engaging below the top bead thereof, the rear edge of said hearth plate being secured to said supporting plate flange, a sheet metal plate disposed with its upper edge against said supporting plate and its lower edge on said hearth plate, and a burner mounted on said supporting plate and provided with burner tips disposed in alinement with said burner openings. 70

5. In a gas stove, the combination of sheet metal back and side walls, the side walls having rolls constituting uprights at their front ends, a sheet metal front plate having beads at its top and bottom edges and secured to said side walls by bolts disposed longitudinally through said beads, a sheet metal top overhanging the rear wall and portions of the end walls, arms extending forwardly from said top above the upper edges of said end walls and secured thereto, bolts disposed longitudinally through said uprights and engaging said top arms, a supporting plate having burner openings therein and a depending flange at its front edge resting on said front plate with its flange engaged below the top bead thereof, the rear edge of said hearth plate being secured to said supporting plate flange, a sheet metal plate disposed with its upper edge against said supporting plate and its lower edge on said hearth plate, radiants disposed upon said supporting plate above said burner openings, a fire back mounted on said supporting plate at the rear of said radiants, and a burner mounted on said supporting plate and provided with burner tips disposed in alinement with said burner openings. 80 85 90 95 100 105 110 115

6. In a gas stove, the combination of back and side walls, the side walls having rolls constituting uprights at their front ends, a front plate having beads at its top and bottom edges and secured to said side walls by bolts disposed longitudinally through said beads, a top, front legs disposed below said uprights, bolts disposed longitudinally through said uprights and constituting top and leg retaining members, a supporting plate mounted within said walls, a hearth plate mounted on said supporting plate to project forwardly therefrom, radiants 120 125 130

posed upon said supporting plate, a fire back mounted on said supporting plate at the rear of said radiants, and a burner mounted on said supporting plate.

- 5 7. In a gas stove, the combination of back and side walls, the side walls having rolls constituting uprights at their front ends, a front plate having beads at its top and bottom edges and secured to said side walls by 10 bolts disposed longitudinally through said beads, a top, front legs disposed below said uprights, bolts disposed longitudinally through said uprights and constituting top and leg retaining members, a supporting 15 plate mounted within said walls, a hearth plate mounted on said supporting plate to project forwardly therefrom, and a burner mounted on said supporting plate.
8. In a gas stove, the combination of back 20 and side walls, the side walls having rolls at their front ends, a front plate having beads at its top and bottom edges and secured to said side walls by bolts disposed longitudinally through said beams, a top, 25 front legs disposed below said uprights, bolts disposed longitudinally through said uprights and constituting top and leg securing members, and a hearth plate extending rearwardly from said front plate.
9. In a gas stove, the combination of sheet

metal back and side walls, the side walls having rolls in their front ends, a front plate secured to said side walls at the rear of said rolls and constituting a bracing member for the side walls, arms disposed on the upper 35 edges of said side walls, front legs disposed below said rolls, and bolts disposed longitudinally through said rolls and securing said arms and legs in position, the rear ends of said arms being secured to said side walls. 40

10. In a gas stove, the combination of a sheet metal back and side walls, a supporting plate having burner openings therein and mounted within said walls, a burner mounted below said supporting plate and having a 45 plurality of burner tips disposed below said openings, radiants disposed on said supporting plate above said burner openings, and a fireback 50 having extensions at its ends projecting forwardly beyond the end radiants to protect the end walls.

In witness whereof, I have hereunto set my hand and seal in the presence of two 55 witnesses.

ALFRED H. HUMPHREY. [L.S.]
